UMBRELLA RIB TIP

Rose H. Morton, New York, N. Y.

Application May 8, 1946, Serial No. 668,075

3 Claims. (Cl. 135—36)

1

This invention relates to improvements in umbrella rib tips.

Many umbrellas at present in use employ a metallic rib with a tip composed of a plastic material having an ornamental upper head portion, usually of substantially spherical configuration, a cylindrical lower portion or skirt provided with an axial socket for the reception of the outer end of the rib, and a transverse thread-receiving opening disposed above the axial socket and below the head. The cover of the umbrella is initially secured to the tip, and after the thread is stitched through the thread-receiving opening, the tips are applied to the tops or outer ends of the ribs. In the operation of applying the tips to the ribs, the fabric is stretched sufficiently to permit the sockets of the tips to be slipped over the ribs, and each of the sockets has a length that, upon contraction of the fabric, will be held tight on the rib. The slight elasticity or stretch of the fabric is thus relied upon to retain the tips and umbrella cover attached thereto in connection with the outer ends of the ribs, particularly when the umbrella is in folded condition. Obviously, if the fabric is, in folded condition, again stretched beyond a predetermined degree, the tip will slide off the mounting portion of the rib. On the other hand, the tip is always tightened when the umbrella is in extended position.

It will be obvious from the above that the length of the socket-containing skirt portions must be definitely limited to a length which is not greater than the difference between the ends of the fabric wings in their normal and stretched conditions respectively, and this skirt portion is usually about one-quarter of an inch.

One of the objects of this invention is to provide a construction in which the tip of the type described will be retained in firmly mounted position at all times on the top of the rib irrespective of the stretch of the fabric, and the aforesaid limitation of the length of the rib-engaging skirt and socket is negatived.

Another object of this invention is to provide a construction by which the length of the rib-engaging socketed skirt may be increased to any desirable degree, and preferably to a degree much greater than any possible stretch of the cloth.

Another object of my invention is in a device of the character specified to provide, in combination with a tip having an initially socketed skirt portion, of an extension socket member by which the length of the rib-engaging socketed skirt will be much greater than any possible stretch of the fabric, and consequently the tip will be

2

firmly and securely held on the rib and it will be impossible for a tip, while connected to the cover, to come off the end of the rib.

With these and other objects in view, the invention comprises the combination of members and arrangement of parts so combined as to contact and cooperate with each other in the performance of the functions and the accomplishment of the results herein contemplated, and comprises in one of its adaptations the species or preferred form illustrated in the accompanying drawings, in which:

Fig. 1 is a view in perspective of an umbrella embodying the features of my invention;

Fig. 2 is a sectional view of my tip and extension socket member in separated relationship;

Fig. 3 is a view partly in section and partly in elevation showing my tip and cover connected and my extension socket member initially applied to and mounted on the rib;

Fig. 4 is a view similar to Fig. 3 showing the rib and extension socket member fastened together;

Fig. 5 is a view partly in section and partly in elevation of a modified form of connection between the tip and extension socket member; and

Figs. 6 and 7 are sectional views, partly in elevation of still another modified form of connection between my tip and extension socket member.

Referring now to these drawings, which illustrate a preferred embodiment of my invention, 1 indicates a conventional umbrella cover with conventional fabric wing sections 1^a and 2 indicates 35 a conventional frame which includes the usual stick 3 and tubular slide 4, the radiating braces 5 and the ribs 6 which are usually composed of metal. In certain types of umbrella, each of the ribs is provided with a separate tip, and my invention relates to umbrella tips of this separable type. In accordance with my invention, each of the tips is of two-part construction and comprises 40 a primary tip member 7 composed of an ornamental tip portion or head 7^a, a skirt or rod-engaging portion 7^b having an axial socket 7^c and an intermediate portion 7^d having a transverse thread-receiving opening 7^d. The socket 7^c is adapted to receive the reduced cylindrical end sections 6^a of the rib 6, each rib, according to 45 the usual practice, being of channel conformation (except a rounded or cylindrical section 6^a at the outer end) and having the open edges of the channel presented inwardly and the arched end of the channel contacting the fabric 1 and extending outwardly for contact therewith. The tip

7 is in the usual practice connected with the said fabric 1 through the transverse aperture 7^a.

In conventional practice, the tip is sewn to the wing sections of the fabric and the fabric is stretched at least the length of the rib-engaging skirt portion to permit insertion of the end 6^a of the rib 6 in the socket of the said skirt portion of the tip.

In accordance with my invention, an extension skirt member 8 having an extension socket is initially mounted on the rib 6 before the application or insertion of the cylindrical end portion 6^a into the socket 7^a, and after such insertion, the extension socket member 8 is moved upwardly and slipped over the outer surface of the tip member 7 and securely fastened thereto or interlocked therewith. Obviously, a primary tip member of substantially conventional conformation may be employed and the conventional procedure of sewing the primary tip member may be followed, but, if desired, the skirt portion of the primary tip member may be reduced in length or substantially eliminated, though it is desirable to provide on the primary tip member a skirt portion to enable initial mounting thereof on the rib.

Many types of connection may be employed for fastening the extension skirt-member to the primary tip member, and in Figs. 2, 3 and 4 I have shown a screw-threaded connection with a short external screw-thread on the outer surface of the tip member 7^a and an internal screw-thread 8^b in the socket of the extension skirt-member 8.

In Fig. 5 I have shown a modified form of my invention in which the tip member and the extension socket member are connected together by a driving fit, the external and internal connecting surfaces preferably being slightly tapered. As both members are preferably formed of plastic material, a suitable glue may be provided to fasten or lock the two parts permanently in position.

In Figs. 6 and 7 I have shown another modified form in which an extension socket member 8^a is provided with an inwardly extending rib 8 which is forced over the surface of the skirt portion of a tip 7^a having a groove 7^a, into which the internal cylindrical rib 8 snaps to produce a snap-lock interlocking engagement.

This construction may be considered my preferred construction as it has an advantage in that the rib 8 will engage and rest on the rib-shoulder 8^b when initially applied to the rib and will thus maintain a fixed position on the rib till fastened to the primary member.

Having described my invention, I claim:

1. A tip for umbrellas comprising, in combination, a primary tip member composed of an upper portion having a head, a lower skirt portion of substantially cylindrical conformation having an axial socket and an intermediate portion having a transverse thread-receiving opening, and an extension skirt member provided with a socket continuous with the socket of said primary tip member, and interengaging connection means on said skirt portion of the primary tip member and on the extension-skirt member for fastening the two members together.

2. A tip for umbrellas comprising, in combination, a primary tip member composed of an upper portion having a head, a lower skirt portion of substantially cylindrical conformation having an axial socket and an intermediate portion having a transverse thread-receiving opening, and an extension skirt member provided with a socket continuous with the socket of said primary tip member, and interengaging connection means on said skirt portion of the primary tip member and on the extension-skirt member for fastening the two members together comprising a groove in one of said members and a snap in-rib on the other member.

3. A tip for umbrellas comprising, in combination, a primary tip member composed of an upper portion having a head, a lower skirt portion of substantially cylindrical conformation having an axial socket and an intermediate portion having a transverse thread-receiving opening, and an extension skirt member provided with a socket continuous with the socket of said primary tip member, and interengaging connection means on said skirt portion of the primary tip member and on the extension-skirt member for fastening the two members together comprising an external groove on the skirt portion of the primary tip member and an internal rib on the extension skirt member.

ROSE H. MORTON.
